UNITED STATES PATENT OFFICE.

GEORGE W. BULL, OF STETTLER, ALBERTA, CANADA.

PRUNING DEVICE.

1,125,057.

Specification of Letters Patent. Patented Jan. 19, 1915.

Application filed June 24, 1913. Serial No. 775,487.

To all whom it may concern:

Be it known that I, GEORGE W. BULL, of the town of Stettler, in the Province of Alberta, Canada, have invented certain new and useful Improvements in Pruning Devices, of which the following is a specification.

The object of my invention is to devise a pruning implement which is equally well adapted to cut small yielding twigs or comparatively large branches, and which will in either case produce a clean cut without bruising or tearing the bark.

With this object in view my invention consists essentially of the construction hereinafter described and specifically claimed.

Figure 1 is a side elevation of my improved implement in its normal position. Fig. 2 is a similar view showing it in a position in which it has completed a cut. Fig. 3 is a similar view of part of the implement taken at right angles to Figs. 1 and 2. Fig. 4 is an enlarged longitudinal section of the upper end of the sliding jaw.

In the drawings like numerals of reference indicate corresponding parts in the different figures.

1 represents the handle of the instrument, which is preferably provided with an extension 2 which may be connected whenever desired by means of the ferrule 3. The upper end of the handle has secured thereto the guide 4, in which there is longitudinally movable the shank 6 of the sliding jaw 7. A guide 5 is formed on the shank 6 and slides on the handle 1. This jaw it will be seen is substantially U-shaped to receive the twig or branch cut off, and faces outwardly and laterally.

Pivoted to the sliding jaw to one side of and above the bottom of the same is the pivoted knife 8. The cutting edge of this knife is curved as shown, but the curve is eccentric to the pivot 9, so that a gradual shearing cut is given when the knife is rocked relatively to the jaw, as indicated in Fig. 2, in which in dotted lines I show the position of the pivoted knife at the end of the cutting operation. The knife is given its motion through the following means: A bracket 17 is secured to the handle and the connecting rod 10 is pivoted thereon at 11. The upper end of this connecting rod is

pivoted at 12 to the knife 8. From this construction it will be seen that if the jaw 55 7 is fitted against the branch and the handle 1 be pushed upon, the shank 6 will slide on the handle, and that the parts will assume the position shown in Fig. 2, the power of the operator being exerted through the medium of the handle and the connecting rod 10 to rock the knife 8 relatively to the jaw and so cut the branch.

A coil spring 13 is connected at one end with the knife and at the other end with the lower end of the shank 6. This spring thus tends to maintain the parts in the position shown in Fig. 1. Sometimes a springy branch will not afford sufficient resistance to enable the device to be operated by a push on the handle. I therefore provide the cord 14 which is suitably arranged to draw down the shank 6 and thus operate the implement. To avoid friction and to increase the purchase I provide a sheave 15 75 at the lower end of the shank 6 and the sheave 16 on the handle 1. The cord 14 is secured at one end to the lower end of the shank 6, passes around the sheave 16, then around the sheave 15, and thence to the operator's hand. This arrangement gives ample purchase to operate the device by a pull on the cord and a light push on the handle at the same time. The jaw 7 it will be noticed is beveled downwardly from the edge which cooperates with the knife. This gives it a sure grip on the branch being cut and prevents slipping which would be liable to bruise the bark.

What I claim as my invention is: 90
In a pruning implement, the combination of a handle; an outwardly and laterally facing sliding jaw movable lengthwise of the handle, a knife pivoted directly on the jaw to one side of and above the bottom and 95 also above the end of the other side of the jaw and having an eccentric curved cutting edge, a connecting rod pivotally connected at one end to the knife and at the other to the handle, and a spring tending to maintain the parts in their normal position.

Toronto this 18th day of June 1913.

GEORGE W. BULL.

Signed in the presence of—

A. CAMPBELL,

E. P. HALL.
